METHOD OF ENCLOSING LAMPSHADES
Manuel G. Rosenthal, R.F.D. 2, Peekskill, N.Y.
Filed July 10, 1958, Ser. No. 747,712
1 Claim. (Cl. 29—450)

This invention relates generally to lamp shade protective covers, and more particularly to novel forms of covers particularly adapted to enclose substantially all of the exposed surface of the same.

While it is known in the art to wrap thin strips of cellophane or similar material about the hollow cylindrical portion of a lamp shade, such procedure has not been entirely satisfactory. With passage of time, the cellophane loosens, permitting gaps to occur in the protected areas through which dirt, soil and moisture may pass to result in soiling both the inner and outer surfaces of the shade. Another disadvantage has been found in the high degree of manual labor and skill in fitting such covers, the winding operation requiring the passing of the hands through the openings in the lamp shade a relatively large number of times.

Other covers have been employed in the art, which are relatively simple to install, but such covers have suffered from a disadvantage in that they are adapted to protect only the outer surface of the shade, permitting dirt or soil to enter the upper and lower openings in the shade to soil the inner surface thereof.

It is therefore among the principal objects of the present invention to provide improved lamp shade covers in which the above-mentioned disadvantages have been substantially eliminated.

Another object of the invention lies in the provision of improved lamp shade covers of the class described which lend themselves to rapid and convenient installation and removal, thus suiting the same for use in connection with the commercial production of lampshades.

Another object of the invention lies in the provision of lampshade covers of the class described in which the number of sizes of the same which must be manufactured to cover a complete range of sizes of lampshades has been materially reduced owing to the incorporation of provisions for adjusting the size of the cover in installed condition within a substantial range of lengths and diameters.

A further object of the invention lies in the provision of inside-outside type lampshade covers possessed of the above advantages, in which the cost of fabrication may be of a reasonably low order, with consequent wide sale, distribution and use.

A feature of the invention lies in the ready adaptability of cylindrically shaped lampshade covers embodying the invention for use in connection with lampshades of frustoconical, octagonal, polygonal and other irregularly shaped shades in limited use at the present time.

These objects and features, as well as other incidental ends and advantages, will become more fully apparent in the progress of the following disclosure, and be pointed out in the appended claim.

On the drawing, to which reference will be made in the specification, similar reference characters have been employed to designate corresponding parts throughout the several views.

FIGURE 1 is a view in perspective showing a first embodiment of the invention in condition prior to installation upon a lampshade cover.

FIGURE 2 is a view in perspective showing a first step in the installation of the cover shown on FIGURE 1 upon a conventional lampshade.

FIGURE 3 is a sectional view showing a second step in the installation of the lampshade cover upon a lampshade.

FIGURE 4 is a similar sectional view showing a third and final step in the installation.

FIGURE 5 is an exploded view in perspective showing a second embodiment of the invention.

FIGURE 6 is a fragmentary view in perspective showing an alternate form of the second embodiment.

5 FIGURE 7 is a view in perspective showing a third embodiment of the invention.

FIGURE 8 is a view in perspective showing an alternate form of the third embodiment.

10 FIGURE 9 is a view in perspective, partially broken away to show detail, showing a final step in the assembly of the alternate form of the third embodiment of the invention upon a frustoconical lampshade.

FIGURE 10 is an enlarged fragmentary vertical sectional view as seen from the plane 10—10 on FIGURE 9.

15 FIGURE 11 is a fragmentary view in perspective showing a second alternate form of the third embodiment.

FIGURE 12 is a fragmentary view in perspective showing a third alternate form of the third embodiment.

20 FIGURE 13 is an enlarged fragmentary view in perspective showing a portion of a fourth embodiment of the invention.

FIGURE 14 is a fragmentary view in perspective showing the fourth embodiment in installed condition.

25 FIGURE 15 is a fragmentary exploded view in perspective showing certain details of the fourth embodiment in disengaged condition.

FIGURE 16 is a similar fragmentary view in perspective showing the disengaged elements of FIGURE 15 in engaged condition.

30 FIGURE 17 is an enlarged fragmentary view in perspective showing the second embodiment of the invention in engaged condition.

FIGURE 18 is an enlarged fragmentary sectional view as seen from the plane 18—18 on FIGURE 14.

35 In accordance with the first embodiment of the invention as seen on FIGURES 1 to 4, inclusive, the device generally indicated by reference character 20 is the form of an elongated cylindrical tube of suitable synthetic material, as for example, polyethylene, cellulose acetate, cellulose nitrate, and the like. The tube 20 is bounded by a first edge 21 having a binding 22 in which a resilient contractile means 23 is disposed. The second edge 24 thereof is generally free of interconnection, and has extending therefrom a plurality of slits 25 arranged generally normally with respect to the plane in which the edge 24 is disposed.

40 Referring to FIGURE 2 in the drawing, there is shown a conventional lampshade 26 of generally cylindrical shape including an upper edge 27, a lower edge 28, an outer surface 29, an inner surface 30 and lampshade supporting means 31 of well known type. In the first step of installation of the device 20 upon the lampshade 26, the first edge 21 is expanded to a degree where the same may be slipped over the lower edge 28, a short distance, following which the second edge 24 is moved upwardly through the lower opening formed by the edge 28.

45 Referring to FIGURE 3, the edge 24 is oriented so that a number of the slits 25 are aligned with supporting means 31 permitting the edge 24 to pass upwardly and outwardly around the upper edge 27 of the shade. The portions of the tube 20 adjacent the edge 24 are then folded against the upper portion of the outer surface 29 completely covering the same. There are thus formed a plurality of individual flap portions 24 which are secured in position by a rubber band 36 or similar elastic contractile means. The final step shown in FIGURE 4 on the drawing involves the moving upwardly of the first edge 21 to a point where it overlies the flap portions 34 thus completely enclosing all of the exposed surfaces of the lampshade.

50 It will be understood by those skilled in the art, that the above method may be employed in the case of poly-

gonally shaped lampshades, as well as frustoconically shaped configurations. In each case, the diameter of the tube 20 sufficiently large that the shade will shape the cover to the necessary configuration upon installation.

Referring to FIGURE 5 on the drawing, there is shown a second embodiment of the invention, generally indicated by reference character 43. The second embodiment is in the form of an elongated tube including an upper edge 45 having a binding 46 and elastic contractile means 47 therein. The lower edge 48 includes a similar binding 49 in which there is disposed an expanding metallic split ring 50. Disposed on the outer surface 52 are first, second, third, fourth and fifth binding members 53, 54, 55, 56 and 57, respectively, each having an opening 58 for the insertion of the split ring 50. In the installation of the second embodiment, the upper edge 45 is expanded as indicated on FIGURE 2 in the case of the first embodiment, and the lower edge 48 is moved into position by compressing the split ring 50 to a point where the same may be slipped within the shade and moving the same upwardly to a point where it contacts the lampshade supporting means 31. Following this, the upper edge 45 is moved upwardly to completely enclose the upper edge 27 of the shade 26. Where the device 43 is overly long, the split ring may be removed from the binding 49, and another binding member 53-57 is selected consistent with the proper length. The device 43 is then cut across the axis of the same to obtain the desired length following which the split ring 50 is reinserted through an opening 58 in the selected member 53-57.

In the alternate form of the second embodiment, shown on FIGURE 6 on the drawing, the binding 49 as well as the binding members 53-57 are provided with a plurality of openings which permit the passage of the supporting means 31 and subsequent reinsertion of the split ring 50 to obtain the appearance shown on FIGURE 17 on the drawing.

Referring to FIGURE 7 on the drawing, there is shown a third embodiment of the invention, in which, to avoid needless repetition, parts corresponding to those of the second embodiment have been designated by similar reference characters with the additional prefix "1."

The third embodiment differs from the second embodiment principally in the elimination of the split ring 50 and the substitution thereof of a plurality of peripherally arranged hooks 66 on the second edge 148 thereof.

In the alternate form of the third embodiment shown on FIGURE 8, the tube 70 is of tapered configuration including a first upper conical portion 71 and a second lower conical portion 72. The upper portion 70 includes a first edge 73, a second edge 74, an inner surface 75 and an outer surface 76. The lower portion 72 is interconnected at a first edge 77 to the second edge 74, and has a second lower edge 78. The binding 79 is provided with peripheral edge hooks 80, and the lower portion 72 may, if desired, include a plurality of overlapping edges 81 to facilitate the engagement of the device upon a shade. While the device, shown on FIGURE 7, may be used either for cylindrically shaped or frustoconically shaped lampshades, the alternate form of the third embodiment shown in FIGURE 8 is particularly adapted for use in conjunction with frustoconical type shades, the installation of the same upon such a shade being shown on FIGURE 9.

In the alternate form of the third embodiment shown on FIGURE 11 on the drawing, the metallic hooks of the principal and first alternate form are replaced by a

stiff molded synthetic resinous hook 89 which may be sewn to the body of the tube as illustrated.

In the third alternate form of the third embodiment shown in FIGURE 12, the hooks are of a flexible nature, 5 as indicated by reference character 90, the same all being part of a continuous bendable wire 91 which is sewn within the binding 92.

Referring now to FIGURES 13, 14, 15, 16 and 18, 10 the fourth embodiment of the invention includes an edge 97 having a lampshade support engaging member 98 stitched thereon by stitch means 99. The reinforcing member 98 may be formed of a suitable stiff material, 15 as for example paper or cellulose acetate, vinyl or the like, and includes an upper edge 100, a lower edge 100' as well as end edges 102, the last mentioned edges being provided with interconnecting tabs 103 and 104. A plurality of vertically disposed slots 105 extend downwardly 20 from the upper edge 100 and communicate with horizontal slots 106 having enlarged ends 107 engageable with portions of the lampshade supporting member 31. Where this form of construction is employed, it substitutes 25 for the hook means of the embodiment shown on FIGURES 7, 8 and 9 or the expanding split ring of the embodiments shown on FIGURES 5 and 6.

It may thus be seen that I have invented novel and 30 highly useful improvements in means for enclosing lampshades, whereby the use of inexpensive materials and construction various forms of lampshades in common use today may be completely enclosed to leave substantially no portion thereof exposed to the deleterious action of 35 dirt or soil. The covers may be as readily removed as installed by those possessing only ordinary skill, and without resort to any special tools so that the same are suitable for use in the home as well as in commercial establishments.

I wish it to be understood that I do not consider the 40 invention limited to the precise details of structure shown and set forth in this specification, for obvious modifications will occur to those skilled in the art to which the invention pertains.

I claim:

The method of installing a cover upon a lampshade 45 comprising the steps of: providing a cover including a substantially cylindrical tube having a principal axis, first and second end edges, the first end edge having resilient contractile means thereon, said second edge having 50 extending therefrom into the material of said cylinder a plurality of axially parallel slits; expanding the resilient means on said first edge and slipping the same over a first portion of the outer surface of said shade; passing the second edge of said cover through the lower opening of said shade and then through the upper opening therein in such manner that the lamp engaging means on said shade engages certain of the slits adjacent said second edge; securing the areas in which said slits are disposed on the upper outer surface of the said lampshade cover; moving said first edge on said cover upwardly to overlie 55 said second edge whereby said lampshade may be completely enclosed.
